UNITED STATES PATENT OFFICE.

ERNEST M. CRANE AND CHAUNCEY R. PELTON, OF DETROIT, MICHIGAN.

DESIGN FOR A CABINET FOR ELECTRICAL APPLIANCES.

51,365.

Specification for Design.

Patented Oct. 16, 1917.

Application filed March 27, 1916. Serial No. 87,134. Term of patent 7 years.

To all whom it may concern:

Be it known that we, ERNEST M. CRANE and CHAUNCEY R. PELTON, citizens of the United States, residing at Detroit, in the county of Wayne and State of Michigan, have invented a new, original, and ornamental Design for a Cabinet for Electrical Appliances, of which the following is a specification, reference being had to the accompanying drawing, forming part thereof.

The figure is a perspective view of the cabinet for electrical appliances, showing our design.

We claim:—

The ornamental design for cabinet for electrical appliances as shown.

ERNEST M. CRANE.
CHAUNCEY R. PELTON.
